(74) Attorney, Agent, or Firm—Kenneth H. Ohriner; Perkins Coie LLP

(57) **CLAIM**

The ornamental design for an umbrella shelter, substantially as shown and described.

DESCRIPTION

FIG. 1 is a perspective view showing my new design.

FIG. 2 is a top view.

FIG. 3 is a bottom view.

FIG. 4 is a rear view. The front view is the same as the rear view; and,

FIG. 5 is a left side view.

The right side view is a mirror image of the left side view.

The shaded areas in FIG. 3 are screen mesh and are not claimed.

The broken lines are for illustrative purposes only and form no part of the claimed design.
